UNITED STATES PATENT OFFICE.

CYRUS L. BUCKWALTER, OF LOUDONVILLE, OHIO.

AIR-SHIP.

No. 861,017.

Specification of Letters Patent.

Patented July 23, 1907.

Application filed February 28, 1907. Serial No. 359,927.

To all whom it may concern:

Be it known that I, CYRUS L. BUCKWALTER, a citizen of the United States, residing at Loudonville, in the county of Ashland and State of Ohio, have invented 5 certain new and useful Improvements in Air-Ships; and I do declare the following to be a full, clear, and exact description of the invention, such as will enable others skilled in the art to which it appertains to make and use the same.

10 This invention relates to flying machines, and more particularly to the means or mechanism for controlling the movement of the same while in the air.

The object of the invention is to provide mechanism that will be simple, strong and easy of manipulation 15 and under the control of the navigator or operator at all times, whereby the course of the machine through the air may be directed at will.

In the accompanying drawings, which illustrate the invention, Figure 1 is a broken side elevation of the 20 machine; Fig. 2 is a top plan view of the same, some of the parts being omitted; Fig. 3 is a transverse sectional view of the machine; Fig. 4 is a broken perspective view of the rack mechanism, separated, for controlling the wings; Fig. 5 is a section of one of the wings; Fig. 25 6 is an enlarged top plan view of the steering mechanism; Fig. 7 is a transverse sectional view of the same; and Fig. 8 is a broken elevation showing a modification of the driving mechanism.

Referring more particularly to the drawings, 1 indicates the body or basket of the machine, which is preferably substantially boat-shape, which is made as light 30 as possible, as by means of a suitable frame and textile or other material stretched upon the same. Rigidly secured at its ends to the sides of the frame at the top 35 of the basket, are two transverse hollow rods, or bars, 2, each of which is provided at a suitable point, preferably substantially midway of its length, with a rack, 3, by means of which the vertical movement of the machine is controlled. Rotatably mounted in each of the 40 hollow members, 2, is a shaft, 4, each end of which is provided with a double crank, 5, and with a drive pulley, 6. Pivots mounted upon each end of each member, 2, is a standard, 7, the upper end of which is provided with a hollow socket, 8, within which is reciprocity mounted a sleeve, 9. The sleeve is connected 45 with one bend of the crank, 5, by means of a pitman, 10, whereby the sleeve will be reciprocated in the socket when the shaft, 4, is rotated. Reciprocally mounted in the sleeve, 9, is a smaller sleeve, 11, which has its lower end connected with the other bend of the 50 crank, 5, by means of a pitman, 12. The bends of the crank are preferably arranged substantially opposite each other so that the sleeves, 9, and 11, will be simultaneously reciprocated in opposite directions, relatively to each other.

The upper end of each sleeve is provided with an umbrella-like frame, 13, between the ribs of which are pivotally secured vanes or feathers, 14, which are adapted to open when the frames are moved upward, and are adapted to be closed automatically when the frame 60 moves downward, the frames and feathers thus forming wings, by means of which the upward movement of the basket can be controlled. The feathers, 14, may be connected with the ribs, 13, in any desired manner, but I prefer to arrange brace rods, 15, between the adjacent 65 ribs, and pivotally secure one edge of the feather thereto, which will permit the free edge of the feather to engage with the next cross-piece below it, and thereby prevents its further upward movement when the wing is moved downward. . . . .

A rod, 16, is preferably extended down through the inner sleeve, 11, with its lower end bent outwardly through slots in both sleeves and secured to the socket, 8, as shown at 17. Brace rods, 18, connect the upper ends of the rods, 16, and thereby add sufficient strength 75 and rigidity to the structure to prevent the wings from moving out of their proper vertical direction when they are reciprocated. Additional strength is also secured for the structure at the lower ends of the posts or brackets, 7, by means of a bar, 19, which is rigidly 80 secured to the top of the basket upon each side, in any desired manner, as by means of bolts, and its ends are preferably slightly bent inward so as to encircle the member, 2, adjacent to the posts, 7.

The posts, 7, are held in any desired vertical position by means of a controlling lever, 20, which is preferably pivotally mounted at its lower end upon the rod, 2, as shown in Fig. 3, and has its mid portion provided with a pawl, 21, which is adapted to engage with or be disconnected from the rack, 3, when the ordinary thumb latch, 22, is actuated, as will be understood. The rack, 3, is preferably made double, with one part located upon each side of the lever, 20, and the ends of the pawl extended so as to engage with the teeth of both portions of the rack simultaneously. A 90 bracket or sleeve, 23, is reciprocally mounted on the racks, 3, by means of wings or flanges, 24, and is pivotally connected with the handle, 20, by means of a pin through forwardly projecting perforated ears, 25. A bar, 26, is pivotally connected with the forward end of the rear sleeve, by means of perforated ears, 27, at one end, and with the rear end of the forward sleeve by means of perforated ears, 28, similar to the ears, 25, of the rear sleeve. As the movements of the forward sleeve are controlled entirely by the movements of the rear sleeve through the rod, 26, the forward racks, 3, are formed without teeth, and the pawl mechanism is omitted from the sleeve. A transverse rod, 28, is secured at its end to two of the oppositely located 105 sockets, 8, and has its middle portion connected with 110

one of the sleeves as by being passed loosely through a transversely perforated lug, or projection, 29, whereby the angle or vertical inclination of the wings may be changed at will by means of the lever, 20, and held 5 in that position as long as desired.

Reciprocating motion can be transmitted to the wings in any desired manner; but I prefer to provide a shaft, 31, which is journaled transversely of the basket, substantially midway between the shafts, 4, with 10 its ends journaled in bearings in the braces, 19. Two drive wheels, 32 and 33, are rigidly secured to the ends of the shaft, 31, in alinement with the pulleys, 6, upon the shafts, 4, whereby the pulleys upon the different shafts are connected by means of belts or sprocket 15 wheels in the usual manner. Motion is transmitted to the shaft, 31, in any suitable manner, an engine, 34, either electric or gasoline, being shown in Fig. 1, mounted upon the floor of the basket and connected with said shaft by means of pulleys, 35, and belting, 20 36. The movements of the engine are controlled by means of a treadle mechanism, 37, in any well-known manner.

If desired, the shaft, 31, may be driven by manual power by substituting ordinary foot mechanism, similar 25 to the ordinary bicycle, for the engine, 34. In this structure, a seat can be provided upon which the operator could sit in position for actuating the pedal mechanism, and also within reach of the mechanism for controlling the movements of the machine, as indicated at 38, in Fig. 8.

The course or direction of the machine is controlled by means of a tail or vane, which projects rearwardly from the rear end of the machine and in position to be under the control of the operator at all times. The 35 tail is composed of two oppositely extending depending flanges, 39 and 40, which are mounted upon a shaft, 41, which is rotatably and pivotally supported by means of a post, 42, which extends down through ears or brackets, 43, at the rear end of the machine. One 40 of the vanes is rigidly secured to the rod, 41, and the other one is loosely mounted thereon, as by means of ears, 44, the forward ear forming a sleeve which is rotatably mounted in a hollow bearing, 45, and the bearing is pivotally mounted in ears, 46, at the upper end 45 of the post, 42 by means of trunnions, 47. A handle bar, 48, is rigidly secured to the forward end of the rod, 41, whereby the movements of the vane, 39, can be controlled, and a handle, 49, is rigidly secured to the forward end of the sleeve, 44, whereby the movements of 50 the vane, 40, may be controlled. A spring, 50, is secured to the handle, 49, and has its free end provided with a toothed segmental part, 51, with which a latch, 52, is adapted to engage and thereby lock the two arms 55 in any desired position, relative to each other. A thumb latch, 53, is provided at the end of the handle, 48, for disengaging the spring and the latch, and thereby permitting the movements of the arms relative to each other for the purpose of spreading the vanes, 39 and 40, away from each other or moving their free edges 60 inward.

A segmental rack, 54, is secured to or formed upon one of the ears, 46, of the standard, 42, and a sleeve, or collar, 55, is reciprocally mounted upon the forward end of the hollow bearing, 45, and provided with a 65 latch, 56, which is adapted to engage with the teeth

of the rack, 54. The sleeve, 55, is prevented from rotating on the bearing, 45, by means of an ordinary feather, 57, and its reciprocation to cause the latch, 56, to engage with or be disconnected from the rack, 54, is controlled by a thumb latch, 58, adjacent to the forward end of the handle, 49, and is connected with the sleeve by means of a connector, 59, and an arm, 60.

The connector 59 is loosely joined at its ends to the arm 60 and the latch 58 so as to permit of a vertical movement of the handle 49 without interfering with 70 the engagement of the latch 56 with the rack 54, and especially in view of the fact that the connection of the connector with the latch 56 is near the axis of rotation of the handle 49. The pivotal arrangement of the thumb latch 58 with the handle will also assist in this movement, as will be readily understood.

As above described, it is evident that when my improved flying machine is in the air, its movements can be controlled by the operator at all times, as he can control the motive power by his foot, or feet, and can 85 control the inclination of the wings by setting them with one hand and locking them in that position and then controlling the movements of the tail by means of both hands, the handles for controlling the tail being preferably curved forward so as to be located, one upon 90 each side of the operator, whether he is sitting or standing in the basket. As the wings are to be reciprocated at a very high rate of speed, the power is preferably secured by means of an engine, which will also give the operator greater freedom for controlling the movements 95 of the machine by means of the wings and tail.

The inclination of the wings can be changed to the front or rear, by moving the lever, 20, forward or back and locking it in that position, which will cause the machine to ascend or descend in accordance with said 100 inclination. By causing the wings to be simultaneously reciprocated in opposite directions, relative to each other, one of the wings of each set will be always descending and exerting its lifting force, while the other one is ascending to be in position for exerting its power 105 when the first-mentioned wing is rising, thereby securing a uniform exertion of power which will have a tendency to raise the machine at a greater or less speed in accordance with the rapidity with which the wings are reciprocated. The tail is so mounted that its rear 110 end can be moved vertically or laterally, simultaneously or independently, and the inclination of the wings can be changed or varied at any time during said movements, or when the position of the tail is held stationary, the angle of the two wings may be varied 115 without changing their relative position to each other, by means of the handles at the forward ends of their support.

Having described my invention, I claim:

1. In flying machine mechanism, a basket, hollow sockets secured thereto, reciprocally mounted sleeves one within the other in each socket, a wing at the upper end of each sleeve provided with feathers, double crank shafts below the sockets and the sleeves, and a pitman from each bend of the crank to the lower ends respectively of said 125 sleeves.

2. In flying machine mechanism, a basket, transversely arranged hollow bars therein, a bracket pivotally secured upon each end of each bar, the upper end of which is provided with a hollow socket, reciprocating sleeves mounted in each socket, a wing at the upper end of each sleeve, a 130

shaft journaled in each hollow bar, the ends of which are each provided with a double crank, a pitman from each bend of said crank to one of said sleeves, and means for swinging said brackets upon said bars to change the inclination of said wings relatively to the basket.

3. In flying machine mechanism, a basket, transversely arranged hollow bars therein, each provided with a segmental rack, a bracket pivotally secured at its lower end to each end of each bar, reciprocatory sleeves mounted in each bracket, a wing secured at the upper end of each sleeve, a shaft journaled in each hollow bar, each one of which is provided with a double crank, pitmen for connecting said cranks with said sleeves, a lever pivotally mounted upon one of said shafts adjacent to the rack thereon, a sleeve upon each rack, one of which is connected with said lever, a rod pivotally connected to said sleeve, and means for locking the lever, rods secured at their ends to said brackets and connecting with the sleeves upon the rack, and means for locking the lever in any desired position.

4. In flying machine mechanism, a body, reciprocatory wings thereon, and a tail pivotally mounted at the rear of the basket, said tail comprising oppositely extending, de-

pendent vanes, and means for moving the rear end of the tail vertically and laterally and controlling the movements of said vanes.

5. In flying machine mechanism, a substantially boat-like basket provided with perforated brackets at its rear end, reciprocatory vanes for the basket, a standard pivotally mounted in said brackets having a hollow bearing 30 and a segmental rack at its upper end, a rod through said bearing, two vanes upon the rear end of said rod, one of which is provided with a sleeve at its forward end which extends through said bearing, two arms at the forward end of said rod, one of which is secured thereto, and 35 the other is secured to said sleeve, a collar reciprocally mounted on said sleeve and provided with a latch in position for connecting with said rack, a thumb piece for moving said collar, and means for locking said handles in any desired position relatively to each other.

In testimony whereof, I have hereunto set my hand in presence of two subscribing witnesses.

CYRUS L. BUCKWALTER.
